UNITED STATES PATENT OFFICE.

NIELS L. MORTENSEN, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR CONTROL.

Application filed June 8, 1921. Serial No. 475,892.

This invention relates to motor control and more particularly to the control of motors to be subjected to variable positive loads and to negative loads which may be of corresponding magnitude, such for example as crane motors and the like.

In the operation of cranes and similar devices it is desirable to provide for lowering of the empty hook or of a light load at a speed equal to or preferably greater than that at which a full load is lowered and the present invention has among its objects that of providing a modified and improved method of motor control enabling such action.

Another object is that of providing such a method whereby the motor speed in either direction may be automatically determined in accordance with the load as ascertained during operation of the motor in a given direction.

Another object is that of providing a method of control of motors employed in the aforementioned and similar service wherein provision is made for automatic preselecting during hoisting, of control conditions suitable for lowering the load hoisted and enabling subsequent subjection of the control for lowering to influence of the preselected conditions while also enabling establishment and maintenance of other control conditions not involving higher operating speeds.

Another object is that of providing apparatus for performance of the foregoing methods.

Another object is that of providing a dynamic braking controller for a hoisting motor enabling preselection of the speed of movement of the load in one or in both directions in accordance with the value of the load as ascertained during movement in a given direction.

Other objects and advantages will herein-after appear.

In the accompanying drawing, wherein are illustrated certain embodiments of the invention in its physical aspects;

Figure 1 is a diagrammatic view illustrating one of the forms thereof;

Figs. 3 and 5 are similar diagrammatic

views illustrating certain modified constructions; while

Figs. 2, 4 and 6 are simplified diagrammatic views corresponding with Figs. 1, 3 and 5 respectively.

According to the instant method it is proposed to effect preselection of the control conditions to be imposed, particularly during lowering, in accordance with effects proportional to the load to be handled, as ascertained during hoisting of the load. Thus, it is proposed in addition to the usual control features, to provide for further speed regulation of the motor, as by field variation, and also to provide for enactment or non-enactment of such special control, dependent upon the value of the load hoisted and also subject to voluntary selection and preselection.

In practice one or more series relays subjected to the motor current, or to another agency proportional to the motor load, may be employed for automatically determining the action as well as the extent of action of the special speed control instrumentalities employed, whereas the usual drum or other controller employed is provided with additional contacts affording voluntary control of such instrumentalities subject, however, to dominant control by the load responsive means.

Referring to Figs. 1 and 2 of the drawing, the same illustrate a reversible, compound motor to be supplied with current from lines L', L'' and comprising an armature A, a series field F and a shunt field F', a brake releasing coil B being arranged to be connected in series with series field F. Steps R' to R'' of accelerating resistance and an additional step R' of dynamic braking resistance are also provided for the motor, while a reversing drum controller serves to commutate the various circuit connections in a well known manner to provide for operation of the motor in reverse directions for hoisting and lowering respectively, also to provide for dynamic lowering of overhauling loads and to maintain the dynamic connections when moved to off position, and also for de-energization of the brake releasing coil.

coil B in said latter position. The foregoing control features being well known and the arrangement of circuits and controller contacts for effecting the same being obvious, 5 no further description of such features is deemed necessary.

In addition to the foregoing, a rheostat 9 is arranged to be in series with the shunt field F' but to be short circuited by the drum controller in all positions of the latter except the off and the final hoisting and lowering positions. Said rheostat is provided with automatic setting or adjusting means comprising a ratcheting device of known construction having operating solenoids 10 and 11 adapted selectively to effect progressive movement of the rheostat arm in opposite directions for increasing and decreasing the value of the rheostat resistance to be connected in circuit.

A pair of series relays 12 and 13, having their energizing coils subjected to the motor current are adapted to control energization of ratcheting solenoids 10 and 11 respectively, the energizing circuits of the latter being subjected to further control by the drum controller. The series relay 12 is normally closed and is calibrated to respond at a lesser value of the motor current than that 30 at which the normally open relay 13 is adapted to respond.

The drum controller is adapted to effect the usual control of the aforescribed motor, including reversal, dynamic braking 35 and lowering all in a manner well understood by those skilled in the art, whereas movement of the drum controller to either of its extreme positions serves to provide the additional effects now to be described.

40 Assuming operation of the motor under the control of the drum controller for hoisting the empty crane hook or the hook carrying a relatively light load, the series relay 13 will remain unresponsive and the series relay 12 will likewise either fail to respond or responding will effect reclosure of its contacts upon or prior to movement of the drum controller to its final hoisting position. Under these conditions the energizing circuit 45 of ratcheting solenoid 11 is uncompleted whereas the energizing circuit of solenoid 10 is completed from line L' through said series relay 12 to and through said solenoid coil thence through contact n of the drum controller to line L². The ratcheting mechanism now acts to increase the effective value 50 of the rheostat resistance thereby weakening the motor shunt field and permitting further acceleration of the hoisting action, 55 it being recalled that the rheostat is in circuit in the assumed position of the drum.

Such adjustment of the rheostat will continue until the resultant weakening of the shunt field permits a sufficient flow of current 60 in the motor circuit to effect response of

series relay 12 whereupon the circuit of solenoid 10 is interrupted terminating the adjusting action.

If, for any reason, the motor current should rise under the aforescribed field weakening action to a value sufficient to effect response of series relay 13 the energizing circuit of the ratcheting solenoid 11 is completed, thereby effecting reverse adjustment of the rheostat with consequent 75 strengthening of the shunt field, and such rheostat adjustment will continue until the resultant value of the motor current is such as to maintain both series relays open, the corresponding setting of the rheostat being 80 thus pre-selected for influencing the control during lowering.

During hoisting of a relatively heavy load such that both series relays are held up while the drum controller occupies its final 85 hoisting position obviously the ratcheting coil 11 is energized and the coil 10 is unenergized, whereby the rheostat 9 is adjusted to strengthen the shunt field until the motor current is reduced to a value such as to permit opening of relay 13 while maintaining the relay 12 likewise open, compensation for possible over-regulation being effected in a manner similar to that just described but in 95 a reverse sense.

Upon moving the drum controller out of the extreme hoisting position aforescribed the circuit of both ratcheting solenoids is interrupted at the contact n thus preventing further rheostat adjustment pending return 100 of the drum to such position. The motor may now be operated under control of the drum for lowering and, for all lowering positions of the drum controller except the last the control is uninfluenced by the aforescribed rheostat setting, the rheostat being short-circuited up to this point. Upon positioning of the drum in said final lowering position, however, the rheostat 9 is inserted in the shunt field circuit thereby effecting a degree of field weakening determined by the aforescribed pre-setting of the rheostat, whereby obviously the final lowering speed is determined by the value of the load as ascertained during hoisting. It 110 is of course to be understood that the controller may be modified to provide for insertion of the field rheostat at any desired point.

Figs. 3 and 4 illustrate a modified controller adapted to provide a similar character of control of a series motor.

In this instance an additional step R^s of resistance is arranged to be connected in series with the motor field upon movement of the drum controller to its extreme position for lowering under conditions of light load.

An electro-responsive switch 20 serves to control exclusion and inclusion of said re-

sistance in circuit. The energizing circuit of switch 20 is controllable jointly by means of contact *p* of the drum controller and by an electro-responsive presetting switch 21, 5 and the circuit of said latter switch is controllable jointly through contact *n* of the drum controller and a series relay 22 subjected to the motor current. Said switch 21 is further adapted to maintain itself closed 10 independently of said series relay but subject to control by the drum controller.

Thus, upon movement of the drum controller to its extreme position for hoisting, if the load and motor current conditions are 15 such as to effect opening of series relay 22 the controller will provide only the usual control features. However, under conditions of light load such as to permit closure of series relay 22 the closing circuit of switch 20 20 21 is established from line L' through the coil of said switch 21 and through said series relay 22 to drum contact *n* and thence to line L². Switch 21 thereupon closes presetting the device to provide the special high 25 lowering speed. Also said switch upon closing maintains itself by way of its upper set of contacts and drum contact *o*, which latter contact is energized for all positions of the drum except the final hoisting position. 30 Thus, following closure of switch 21 the same can be permitted to open only by placing the drum in such final hoisting position with concurrent opening of series relay 22.

The aforescribed closure of switch 21 35 is without influence upon the control effected except upon throwing the drum to the final lowering position whereupon the circuit of switch 20 is completed from line L' through the coil of said switch, through the lower contacts of switch 21 and drum contact *p* to line L². Switch 20 thereupon opens and inserts resistance R^s in series with the motor field, which under lowering conditions is 40 connected in parallel with the armature, 45 thereby weakening the field and permitting the motor to accelerate to a speed higher than that permitted for hoisting.

The controller illustrated in Figs. 5 and 50 6 is in most essential respects similar to that last described, except that in this instance the resistance R^s is arranged to be connected in parallel with the motor field F instead of in series therewith as in the preceding construction.

55 A normally open electro-responsive switch 20^a serves when closed to complete such circuit including said resistance R^s in parallel with the motor field, whereas a presetting switch 21^a serves in conjunction with the series relay 22 and the drum controller to control the opening and closing action of said switch 20^a.

Upon movement of the drum controller 60 to its final hoisting position under conditions of heavy load and correspondingly

heavy motor current the series relay 22 is maintained open and prevents closure of either switches 20^a or 21^a, thus restricting the action of the controller to that ordinarily provided. However, under conditions of 70 light load such as to permit closure of the series relay upon final hoisting positioning of the drum the closing circuit of switch 20^a is completed from line L' through the coil of said switch through series relay 22 75 and contact *n* of the drum controller to line L². Said switch thereupon closes connecting resistance R^s in parallel with the motor field circuit as described and also by means of its lower set of contacts serves to 80 complete a pickup circuit for switch 21^a from line L' through the coil of said switch 21^a and through the lower set of contacts of switch 20^a to drum contact *o* and thence to line L². Said switch 21^a thereupon closes 85 and maintains itself by means of its own upper contacts and through contact *p* of the drum controller, said latter contact being energized for all positions of the drum controller except the final hoisting position, and the aforescribed maintaining circuit being independent of series relay 22. Said switch 21^a upon closure thereof also serves by means of its lower set of contacts to establish partial circuit connections for the closing coil 90 of switch 20^a, subject to completion independently of the position of series relay 22 upon movement of the drum controller to its final lowering position.

Upon movement of the drum controller 100 out of its final hoisting position the switch 20^a is adapted to open thus opening the resistance shunt around the motor field and the character of the control effected is therefore uninfluenced by the aforescribed special features except upon movement of the drum to either its final hoisting or final lowering position. In either of these positions said switch 20^a is closed for re-establishment 105 of such field shunt, closure of such switch 20^a in the final hoisting position of the drum being dependent either upon closure of the series relay 22 or upon continued closure of switch 21^a, whereas closure of said switch 20^a in the final lowering position of the drum is 110 dependent absolutely upon presetting and continued closure of the switch 21^a.

115 Thus, obviously this type of controller provides for acceleration of the controlled motor by means of the field shunt during hoisting as well as during lowering. However, if desired the controller may by obvious expedients be modified to restrict such action to conditions of lowering. Similarly the control provided by the construction of 120 Fig. 1 may be modified for so restricting the action of the special acceleration features provided by merely increasing the length of the drum hoist segment co-operating with contact *o* sufficiently to effect short-circuiting 125 130

of the field rheostat 9 in the final hoisting position.

Again the construction illustrated in Fig. 3 may readily be modified to afford the higher motor speeds for hoisting as well as for lowering, whereas the field rheostat together with its operating means as illustrated in Fig. 1 may, if desired, be substituted in the control schemes illustrated in Figs. 3 10 and 5, while said latter constructions may each be provided with several steps of field resistance having individual control means. Also, if desired, the structure of Fig. 5 may be modified by subjecting the control of the 15 field paralleling resistance to different contactors and series relays under conditions of hoisting and lowering respectively, thereby permitting attainment of a higher motor speed for lowering than that permitted for 20 hoisting. Finally it is obvious that the full electrical control aforescribed may be substituted wholly or in part by mechanical devices associated with and operable by the drum controller for attainment of the effects 25 aforescribed.

The various circuit connections commutated by the individual forms of controller are illustrated in the simplified diagrams of Figs. 2, 4 and 6 whereas the sequence of operation of the various controller parts is depicted in the corresponding complete diagrams.

What I claim as new and desire to secure by Letters Patent is:

35 1. The method of control of a motor to be subjected cyclicly to conditions of positive and negative load, which comprises comparing the value of the load during a given portion of the operating cycle with a standard value and pre-arranging for control of the motor during a subsequent portion of its operating cycle in accordance with the degree of departure of the load from such standard value.

45 2. The method of control of a motor to be operated in cycles and each cycle including subjection of the motor sequentially to conditions of positive and negative load which comprises electrically comparing the value of the load during a given earlier portion of the operating cycle with a standard value, prearranging control conditions for the motor in accordance with the result of such comparison and enacting the prearranged 55 control during a subsequent portion of the same cycle.

3. The method of control of a reversible motor to be operated in cycles and each cycle to include subjection of the motor sequentially to conditions of positive and negative load, which comprises ascertaining the effect of the load on the power consumption of the motor within a single cycle and prearranging in accordance with the ascertained value the control conditions to be applied to the

motor within the same cycle but under reverse operating conditions.

4. The method of control of a reversible motor to be operated in cycles and each cycle to include subjection of the motor sequentially to conditions of positive and negative load, which comprises ascertaining the effect of the load on the power consumption of the motor within a single cycle, prearranging the character of control to be subsequently applied to the motor in accordance with the ascertained value and applying the prearranged control to the motor while subjected to negative load conditions of the same operating cycle.

5. The method of control of a reversible motor to be operated in cycles and each cycle to include subjection of the motor sequentially to conditions of positive and negative load, which comprises detecting variations in load through the effect thereof on the power consumption of the motor within a single cycle, prearranging in accordance with such variations the character of a control to be subsequently applied to the motor and enacting the prearranged control during subsequent voluntarily determinable periods within the same cycle.

6. The method of control of a reversible motor to be operated in cycles and each cycle to include subjection of the motor sequentially to conditions of positive and negative load, which comprises detecting variations in positive load through ascertaining the effect thereof upon the power consumption of the motor within a single cycle, prearranging in accordance with such variations the character of a control to be subsequently applied to the motor and applying the preselected control to the motor during a subsequent voluntarily determinable period during operation of the motor in either direction within the same cycle.

7. The method of controlling the speed of a motor to be subjected to positive loads which vary from one another and to negative loads each substantially similar in magnitude to a corresponding positive load which comprises detecting variations in the positive load through ascertaining the effect thereof upon the value of the motor current, prearranging in accordance with such variations the character of control to be subsequently enacted, and thereafter enacting the prearranged control under corresponding conditions of negative load.

8. The combination with a motor to be operated cyclicly under different load conditions, of speed controlling means having automatic means to set the same according to load conditions during part of any cycle for preset control during a later part of the same cycle and a master controller for the motor to render control thereof independent of the setting of the former means

or subject to influence thereby according to the positioning of said master controller.

9. The combination with a reversible motor to be operated cyclicly for hoisting and lowering loads of different values, of speed controlling means having automatic means to set the same according to the value of the load being hoisted to afford preset control for lowering and a master controller acting according to the positioning thereof to render said preset control means effective or ineffective during lowering.

10. The combination with a reversible motor to be operated in cycles and each cycle to include subjection of the motor sequentially to conditions of positive and negative load, of control means for the motor comprising means for ascertaining the effect of the load on the power consumption of the motor within a single cycle, and means for utilizing the ascertained effect in prearranging control conditions for the motor within the same cycle but under reverse operating conditions.

11. The combination with a reversible motor to be operated in cycles and each cycle to include subjection of the motor sequentially to conditions of positive and negative load, of control means for the motor comprising means for ascertaining the effect of the load on the power consumption of the motor within a single cycle, means for utilizing the ascertained value in prearranging the character of control to be subsequently applied to the motor, and means for applying the prearranged control of the motor while subjected to negative load conditions of the same operating cycle.

12. The combination with a reversible motor to be operated in cycles and each cycle to include subjection of the motor sequentially to conditions of positive and negative load, of control means for the motor comprising means for detecting variations in load through the effect thereof on the power consumption of the motor within a single cycle, means for prearranging in accordance with such variations the character of a control to be subsequently applied to the motor, and means for enacting the prearranged control during subsequent voluntarily determinable periods within the same cycle.

13. The combination with a reversible motor to be operated in cycles and each cycle to include subjection of the motor sequentially to conditions of positive and negative load, of control means for the motor comprising means for detecting variations in positive load through the effect thereof upon the power consumption of the motor within a single cycle, means for prearranging in accordance with such variations the character of a control to be subsequently applied to the motor, and means for applying the preselected control to the motor during a

subsequent voluntarily determinable period 65 during operation of the motor in either direction within the same cycle.

14. The combination with a motor to be subjected to positive loads which vary from one another and to negative loads each substantially similar in magnitude to a corresponding positive load, of speed controlling means for the motor comprising means for detecting variations in the positive load through the effect thereof upon the value of 75 the motor current, means for prearranging in accordance with such variations the character of control to be subsequently enacted, and means for thereafter enacting the prearranged control under conditions of corresponding negative load.

15. In a control system wherein motors are subjected to positive and negative loads, the combination with means to preselect control conditions for the control of a negative load 85 in accordance with the motor current under conditions of positive load, of means for effecting enactment of the control conditions so preselected.

16. In a hoisting controller for motors, the 90 combination with means for varying the motor field excitation in accordance with the value of the load being hoisted, of control means for said former means comprising a series relay to be subjected to the motor current, a drum controller having parts adapted to provide for operation of said field varying means but only following a given action of said series relay, and means for controlling the motor field excitation during 95 lowering in accordance with the variation thus effected.

17. In a control system wherein motors are subjected to positive and negative loads, the combination with electroresponsive speed 105 varying means for the motor, of control means for said former means subjected to electrical influence in accordance with the positive load upon the motor, and voluntary control means for subjecting said speed varying 110 means to control by said second mentioned means, said voluntary control means being also adapted to utilize the effect of such positive load influence under conditions of negative load.

18. In a control system wherein motors are subjected to positive and negative loads, the combination with adjustable speed control means for the motor, of means for automatically effecting adjustment of said former means in accordance with the positive load upon the motor, and manually operable means for utilizing the aforementioned adjustment under negative load conditions.

19. In a hoisting and dynamic lowering controller for motors, the combination with power operated means including a regulable resistance for varying the field excitation of 125

the motor, of means subjecting said former means to series relay control for varying the motor field in accordance with the value of the motor current during hoisting, and a drum controller having parts adapted to control the operation of said power operated means subject to control by said series relay

control means and further adapted to utilize during lowering the motor field adjustment effected during hoisting.

In witness whereof, I have hereunto subscribed my name.

NIELS L. MORTENSEN.
